UNITED STATES PATENT OFFICE.

JOHANN STUMPF, OF BERLIN, GERMANY.

LOCOMOTIVE WITH THREE CYLINDERS.

Application filed April 17, 1916. Serial No. 91,792.

To all whom it may concern:

Be it known that I, JOHANN STUMPF, a citizen of the German Republic, residing at Berlin, Germany, have invented a new and useful Locomotive with Three Cylinders, of which the following is a specification.

The invention relates to locomotives with three steam cylinders and especially to the arrangement and to the distributing gear of said cylinders.

It is known, in combination with three-cylinder-locomotives, to have the distributing valve of the middle cylinder moved by lever and shaft mechanism from the valves of the side cylinders, for which mechanism there are many modes of execution.

The present invention comprises the arrangement of the two side cylinders of the locomotive, at a common level above the rails, with a middle cylinder mounted at a higher level and with its axis directed downwardly toward its crank shaft, so that underneath said middle cylinder may be arranged the connecting mechanism of the truck or empty running axles, and so that the piston rod and connecting rod of the middle cylinder may pass freely above the several interposed shafts of the wheels.

The invention also comprises the dislocation of the middle crank pin with reference to its normal position, by an angle approximately equal to the angle between the axis of the middle cylinder and the plane of the axes of the side cylinders; so that the distributing and lever mechanism between the side cylinders and the middle cylinder may be used without any alteration.

The object therefore of this invention is to secure a proper positioning of the middle cylinder so as not to interfere with supporting mechanism, and also to provide a simple crank and valve gear arrangement, that will secure the required relative movement of the middle cylinder valve.

Referring to the drawings, which illustrate merely by way of example a suitable embodiment of my invention—

Fig. 1 is a side elevation.

Fig. 2 is a plan view.

Fig. 3 is a side elevation of a modification.

Fig. 4 is a plan view of same.

In all the figures unnecessary parts are omitted for the sake of simplicity.

Similar parts in all figures are indicated by the same reference numbers.

Referring to the arrangement shown in

Figs. 1 and 2, the locomotive comprises a truck with two pairs of wheels 1, 2 and one or more pairs of driving wheels 3. The driving force is given by three steam cylinders 4, 5, 6, of which the cylinders 4, 6 are mounted in the usual manner at the sides of the frame 7, and the third cylinder 5 is arranged between the side cylinders and at a higher level. The axis of each side cylinder is directed horizontally to the crank shaft 8, and the axis of the middle cylinder is inclined downwardly toward the crank shaft 8.

The side cylinders 4 and 6 in Figs. 1 and 2 are fitted with the slide valve casings 9 and 10, upon the upper side, and the middle cylinder 5 is fitted with a slide valve casing 11 at its under side. All the slide-valve casings are mounted horizontally. The slide-valve rods 12 and 13 of the side cylinders, are connected, as at 12^a and 13^a, to any suitable valve operating gear, not shown. These valve rods 12 and 13 are also connected by link rods 14 and 15, to double armed levers 16, 17, which are pivoted on the frame 7. The other ends of the said levers 16, 17 are connected by links 18, 19 to a double armed lever 20, mounted on the slide-valve rod 21 of the middle cylinder.

By the mechanism described, the middle valve rod is moved in such a manner, that its position, in every moment, is the same as though the three crank pins 22, 23, 24, were located for 120° between each other with the axes of the cylinders in the same plane. The middle crank pin 23 now being dislocated with reference to the 120° position, for approximately the same angle as that between the axis of the middle cylinder and the horizontal axis of the side cylinder. The positions of the middle piston, relative to its cylinder 5, in every moment, are the same as if the middle cylinder 5 were located in the same plane as the side cylinders 4, 6, with all cranks placed at 120°.

Each of the double armed levers 16 and 17, has one arm approximately twice as long as the other, and the rods or links 14 and 15, are pivoted to the shorter arms, so as to transfer the movements of substantially the same kind and amount, of the said slide-valve rods 12 and 13 in approximately doubled scale to the combining lever 20 of the middle valve. By this means the movement of the middle valve is correct, and of proper amount, and no doubled diameter of

the slide-valve or double size of the steam ports is needed.

Referring to the modification shown in Figs. 3 and 4, the wheels 1, 2 and 3, and the arrangement of cylinders 4, 5 and 6 are the same as in Figs. 1 and 2; also the slide-valve casings 9 and 10 of the side cylinders have the same arrangement.

The slide-valve casing 11', of the middle cylinder 5, is mounted on the upper side of said cylinder, in the same manner as shown with respect to the side cylinders 4 and 6, and the axis of said middle slide valve therefore is inclined downwardly at the same angle as the axis of the middle cylinder 5.

The lever and shaft mechanism, connecting the valve rods 12, 21 and 13, of the three cylinders, comprises a pair of rocking shafts 20 25 and 26, mounted in bearings on the frame 7. To the rocking shafts 25 and 26 are connected a shorter lever 27, 28 on the outer end, and a longer lever 29, 30 on the inner end of each shaft respectively. The levers 25, 27, 28, 29 and 30 are connected in a similar way, as in Figs. 1 and 2, by link rods 14, 15 to slide valve rods 12 and 13, and by link rods 18 and 19 to the double armed lever 20 pivoted at the middle to slide-valve rod 21. 30 The outer levers 27 and 28 are approximately half the length of the inner levers 29, 30 and the movement therefore is trans-

ferred in the right scale to the middle slide valve, as above explained.

By the term locomotive, as used in this application, I mean to use it in the broader sense, that is, to include all auto-motive engines whether running on rails or not.

What I claim is:—

In a locomotive, the combination of three 40 cylinders, two of which are mounted, one on each side of the locomotive, in a common plane, said side cylinders having cranks placed at substantially 120° apart, a middle cylinder mounted higher than the side cylinders, having its axis at an angle of inclination to said common plane and having its crank dislocated from its normal 120° position at approximately the same angle, said cylinders provided with suitable distribution valves, and each side-cylinder-valve with a suitable valve gear, and means for communicating to the middle cylinder valve a resultant of movements of substantially 50 the same kind and amount, derived from the side cylinder valve gear actuators, in order to secure proper relative distribution to said three cylinders.

In testimony whereof I affix my signature in presence of two witnesses.

JOHANN STUMPF.
